AIR OUTLET DEVICE FOR VENTILATING SYSTEMS

Alfred R. Gilbert, New York, N. Y., assignor to
 Anemostat Corporation of America, New York,
 N. Y., a corporation of Delaware

Application October 26, 1949, Serial No. 123,657

8 Claims. (Cl. 98—40)

1

This invention relates generally to air outlet devices for ventilating systems, and has particular reference to improvements in means for mounting in the necks of such devices adjustable air deflecting units for use in predetermining the pattern of the air delivered from such devices.

Generally speaking, the object of the invention is to provide simple, practical means to facilitate mounting of an air deflecting unit in the neck of any air outlet device and to enable ready and easy removal of the unit from the neck whenever desired for cleaning, adjustment or any other purpose.

An adjustable air deflecting unit of the type with which the present invention is concerned comprises a band or ring and a plurality of vanes extending across the same and pivoted thereto for adjustments to desired air deflecting angles relative to the band or ring and relative to each other. In this connection, a more specific object of the invention is to provide in the neck of an air outlet device, mounting means for an adjustable air deflecting unit of the type mentioned, which mounting means is in the form of spring arms with which the ring or band of the air deflecting unit may readily and easily be engaged to operatively mount said unit in said neck and from which said band or ring may readily and easily be disengaged to permit removal of the air deflecting unit whenever desired.

A well known type of air outlet device for delivering air from an air supply duct into a room or other enclosure for heating, cooling, ventilating or other purposes comprises a plurality of successively smaller, open-ended, hollow, flaring members which are spaced apart successively inwardly of one another and the larger or outermost of which is provided at its smaller or rear end with a neck for connection with an air supply duct. Thus, air supplied to the device through the neck thereof is divided by the flaring members into a plurality of separate streams which are deflected more or less laterally outward from the device by said members and the air thereby is delivered from the device in diffused form. In an air outlet device of this type it is known to connect together as a unitary assemblage all except the outermost of the flaring members and to provide means to mount said unitary assemblage in the larger or outermost flaring member for ready removal therefrom to afford ready access to the neck of the larger or outermost flaring member and thus facilitate connection of said neck with an air supply duct, as well as to facilitate proper mounting of the outlet device

2

as a whole. In this connection another object of the invention is to provide for mounting of the aforementioned spring arms upon said unitary assemblage of flaring members so that when the latter is removed from the larger or outermost flaring member an air deflecting unit may readily and easily be engaged with said spring arms for subsequent operative positioning in the neck of the device by the mere act of mounting said unitary assemblage in the larger or outermost flaring member, and so that in the event an air deflector is already engaged with said arms when said unitary assemblage is removed, said air deflecting unit is removed with said unitary assemblage and thereby is readily accessible for cleaning, adjustment, or any other purpose. Further in this connection, another object of the invention is to mount the said spring arms upon the struts or bars which usually are employed to connect together the flaring members of the unitary assemblage and to removably mount said assemblage in the larger or outermost flaring member, whereby the said spring arms are firmly and securely mounted upon said unitary assem-

25 blage.

With the foregoing and other objects in view, as will become more fully apparent as the nature of the invention is better understood, the same consists in the provision of means for the purpose embodying the novel features of construction, combination and arrangement of parts as are illustrated by way of example in the accompanying drawings and as will be hereinafter more fully described and claimed.

30 In the accompanying drawings, wherein like characters of reference denote corresponding parts in the different views:

Fig. 1 is a rear elevation of an air outlet device having operatively mounted in the neck thereof an air deflecting unit in accordance with the invention.

Fig. 2 is a central, longitudinal section through the outlet shown in Fig. 1.

Fig. 3 is an enlarged section on the line 3—3 of Fig. 1; and

Figs. 4 and 5 are sections similar to Fig. 3 illustrating alternative constructions.

Referring to the drawings in detail, A designates, generally, an air outlet device of a known type with which the present invention is concerned and B designates, generally, an air deflecting unit of a known type for use in connection with an air outlet device such as the device A to predetermine the pattern of the air delivered therefrom.

The air outlet device A comprises a plurality of successively smaller, open-ended, hollow, flaring members 10 which are spaced successively inwardly of one another to provide therebetween a plurality of successively smaller air passageways 11 which flare toward the front or air outlet end of the device.

A neck 12 extends rearwardly from the smaller or rear end of the larger or outermost flaring member 10 for connection with an air supply duct, and when air is supplied to the device through said neck it is divided by the members 10 into a plurality of separate streams which flow through the passageways 11 and are deflected more or less laterally outward from the device by said members 10 depending upon the flare of the latter. The air thereby is delivered from the device in diffused form throughout a substantial area forwardly and laterally relative to the device.

The air deflector unit B comprises a ring or band 13 of a size and shape to be accommodated more or less freely within the neck 12 of the outlet device A, and a plurality of vanes 14 extending in suitably spaced apart, preferably parallel relationship to each other, from side to side of said band and pivoted at their ends to said band, as indicated at 15, or rotative adjustments to different angular positions relative to each other.

The air deflector unit B is designated to be mounted in the neck 12 of the air outlet device A, in a plane at right angles to said neck, to position the vanes 14 so that by proper pivotal adjustments of the same they may be caused to deflect supplied air through desired portions of the passageways 11 and thus predetermine the pattern of the air delivered from the device A.

In an air outlet device A of the type illustrated it is known to connect together as a unitary assemblage all except the outermost of the flaring members 10 and to provide means to removably mount said unitary assemblage in the larger or outermost flaring member 10 to afford ready access to the neck 12 for the purpose of facilitating connection of said neck with an air supply duct and proper mounting of the device A. In this connection and as illustrated by way of example in the drawings, all except the outermost of the flaring members 10 are connected together as a unitary assemblage by a plurality of bars 16 which extend across the smaller or rear ends of said members 10 and are welded or otherwise suitably fastened to said members. The outer end portions of said bars 16 extend beyond the larger or outermost flaring member of the unitary assemblage and are bent to extend forwardly at angles corresponding to the flare of the larger or outermost flaring member 10 of the device A so as to engage flatly against the front face of said larger or outermost flaring member to determine proper positioning of the unitary assemblage of flaring members forwardly and rearwardly relative to said outermost flaring member 10. Moreover, the terminal portions of the bars 16 are bent to extend at substantially right angles to said bars in the planes of the outer end portions of said bars to provide said bars with hook-like extremities 17 for cooperation with suitable sockets 18 with which the larger or outermost flaring member 10 of the device A is equipped to removably mount said unitary assemblage of flaring members in said larger or outermost flaring member 10. The sockets 18 may be provided by U-shaped members 19 riveted, welded or otherwise suitably fastened against the front face of the larger or

outermost flaring member 10 of the device A, as illustrated in Figs. 1, 2, 3 and 5 of the drawings, or they may be provided by forwardly depressing portions 20 of the larger or outermost flaring member 10 of the device A as illustrated in Fig. 4 of the drawings. In any event, it is apparent that the hook-like extremities 17 and the sockets 18 provide means whereby the unitary assemblage of flaring members 10 may readily and easily be mounted in the larger or outermost flaring member 10 of the device A and may equally as readily be disconnected from said larger or outermost flaring member of the device A for removal therefrom, simply by a small amount of rotation of said unitary assemblage of flaring members relative to the larger or outermost flaring member 10 of the device A.

The means for removably mounting the air deflecting unit B in the neck 12 consists of a plurality of spring arms 21 which may, if desired, be permanently mounted in said neck, but which, preferably, are carried by the unitary assemblage of flaring members whereby they are operatively positioned in the neck 12 by mounting of the unitary assemblage of flaring members in the larger or outermost flaring member of the device A and are removed from said neck when said unitary assemblage of flaring members is removed from the larger or outermost flaring member of the device A.

If desired, the arms 21 may be welded, riveted or otherwise suitably fastened to one or more of the flaring members 10 of the unitary assemblage of said members, to the outermost of said members for example. Preferably, however, said arms are fastened to the bars 16, as thereby they are more firmly and securely supported than would be the case if they were fastened directly to one or more of the flaring members 10. In any event, said arms extend rearwardly from the unitary assemblage of flaring members whereby they are disposed in the neck 12 and extend longitudinally thereof when the unitary assemblage of flaring members is operatively mounted in the larger or outermost flaring member 10 of the device A. Moreover, said arms are positioned relative to the unitary assemblage of flaring members so that they are disposed more or less closely adjacent to the neck 12 when said unitary assemblage of flaring members is operatively mounted in the larger or outermost flaring member of the device A. In other words, the relationship of the arms 21 relative to each other is such that they are engageable with the ring or band 13 of the air deflecting unit B at spaced points around said band to support the latter and, hence, said air deflecting unit B as an entirety in its operative position in the neck 12 when the unitary assemblage of flaring members is mounted in the larger or outermost flaring member of the device A.

To adapt the arms 21 to hold the air deflecting unit against longitudinal movement relative to said arms, said arms are provided with off-set portions 22 wherein the ring or band 13 is accommodated and which afford shoulders 23 for engagement with opposite edges of said ring or band. In this connection and as will be understood, the ring or band 13 may be disposed either outwardly or inwardly relative to the arms 21, and the portions 22 of said arms may be offset either inwardly or outwardly to accommodate said ring or band, depending upon whether the latter is disposed outwardly or inwardly of said arms. In any event, the arms 21 are flexible to enable ready and easy engagement and disengagement of the

5

ring or band 13 with the same, and the free end portions 24 of said arms preferably are inclined to guide the ring or band 13 onto said arms.

Fig. 4 illustrates that, if desired, the arms 21^a, instead of the bars 16, may have hook-like portions 17^a for cooperation with the sockets 18; otherwise, the Fig. 4 construction is generally the same as the Figs. 1 to 3 construction. On the other hand, Fig. 5 illustrates that, if desired, the arms 21^b may be permanently fastened in and 10 to the neck 12, in which connection it will be apparent that said arms may be either entirely separate from each other or may be carried by a ring or band 25 as shown. As will also be apparent, the arms 21^b may have their free end 15 portions disposed either rearwardly, as shown, or forwardly if desired.

Whether the arms 21 are mounted permanently in the neck 12 or upon the unitary assemblage of flaring members, it is apparent that the air deflecting unit B is readily engageable with and disengageable from said arms when said unitary assemblage of flaring members is removed from the larger or outermost flaring member of the device A, whereby operative mounting of said air deflecting unit in the neck 12 is greatly facilitated.

Spring fingers 26 fastened against the rear face of the larger or outermost flaring member 10 of the device A and having projections 27 to pass through holes in said larger or outermost flaring member into holes or depressions in the terminal portions of the bars 16 or the arms 21, as the case may be, are employed as a practical means of frictionally holding the unitary assemblage of flaring members against rotation in a direction to disconnect said assemblage from the larger or outermost flaring member of the device A.

From the foregoing description considered in connection with the accompanying drawings, it is believed that the construction, operation and 40 advantages of the means constituting the present invention will be clearly understood. It is desired to point out, however, that while only certain specific embodiments of the invention have been illustrated and described, the same is readily capable of specifically different embodiments within its spirit and scope as defined in the appended claims.

I claim:

1. An air outlet device for ventilating systems comprising an outermost, open-ended, hollow, flaring member having a neck extending rearwardly from its rear end for connection with an air supply duct, at least one other flaring member mounted within and spaced from said outermost flaring member to effect lateral deflection of air supplied to the device through said neck, an air deflecting unit to be mounted in said neck behind said second mentioned flaring member, and leaf spring means carried by said outlet device and disposed in said neck for removably mounting said air deflecting unit in said neck.

2. An air outlet device for ventilating systems comprising an outermost, open-ended, hollow, flaring member having a neck extending rearwardly from its rear end for connection with an air supply duct, at least one other flaring member mounted within and spaced from said outermost flaring member to effect lateral deflection of air supplied to the device through said neck, an air deflecting unit to be mounted in said neck behind said second mentioned flaring member, and spring arms in said neck each fastened at one end to said outlet device and having its other end portion free for resilient holding coopera-

6

tion with said air deflecting unit to removably mount the latter in said neck.

3. An air outlet device as set forth in claim 2 in which the air deflecting unit includes a ring and in which the spring arms extend longitudinally relative to the neck and have offset portions shouldered at their ends to accommodate the ring of the air deflecting unit to removably mount and definitely position the latter in the neck.

4. An air outlet device for ventilating systems comprising an outermost, open-ended, hollow, flaring member having a neck extending rearwardly from its rear end for connection with an air supply duct, at least one other flaring member within and spaced from said outermost flaring member to effect lateral deflection of air supplied to the device through said neck, means to removably mount said second mentioned flaring member in said outermost flaring member, an air deflecting unit to be mounted in said neck behind said second mentioned flaring member, and spring means carried by and extending rearwardly from said second mentioned flaring member to removably mount said air deflecting unit on said second mentioned flaring member and to operatively position said unit in said neck when said second mentioned flaring member is operatively mounted in said larger or outermost flaring member.

5. An air outlet device as set forth in claim 4 in which the spring means to removably mount the air deflecting unit upon the second mentioned flaring member comprises spring arms mounted on and extending rearwardly from said second mentioned flaring member.

6. An air outlet device as set forth in claim 4 in which the air deflecting unit includes a ring and in which the spring means to removably mount said air deflecting unit upon the second mentioned flaring member comprises spring arms mounted on and extending rearwardly from said second mentioned flaring member and having offset portions shouldered at their ends to accommodate the ring of said air deflecting unit.

7. An air outlet device for ventilating systems comprising an outermost, open-ended, hollow, flaring member having a neck extending rearwardly from its rear end for connection with an air supply duct, a unitary assemblage of successively smaller, open-ended, hollow flaring members disposed in said outermost flaring member and spaced successively inwardly from the latter and from each other to divide air supplied to the device through said neck into a plurality of separate streams and to effect lateral deflection of the streams, elements connecting together the flaring members of said assemblage and detachably connected to said outermost flaring member for removably mounting said assemblage in said outermost flaring member, an air deflecting unit to be mounted in said neck behind said assemblage, and spring arms mounted on said elements and extending rearwardly therefrom to removably mount said air deflecting unit upon said assemblage and to operatively position said air deflecting unit in said neck when said assemblage is operatively mounted in said outermost flaring member.

8. An air outlet device as set forth in claim 7 in which the air deflecting unit includes a ring and in which the spring arms have laterally offset portions shouldered at their ends to accommodate the ring of said air deflecting unit.

ALFRED R. GILBERT.
